TEMPERATURE-SENSITIVE HEAT CONTROL UNIT

Walter H. Holzboog, Clayton, Mo., assignor, by mesne assignments, to Micro Controls, Inc., St. Louis, Mo., a corporation of Ohio

Application May 5, 1958, Serial No. 733,189

1. Claim. (Cl. 73—368)

This invention relates to temperature-sensitive heat control units for cooperation with burners of gas cooking ranges and the utensils heated thereby, being an improvement upon the heat control unit shown in the United States patent application of Harold C. Reinhart, Serial No. 686,501, filed September 26, 1957, for Temperature-Sensitive Heat Control Unit, subsequently abandoned.

Among the several objects of the invention may be noted the provision of a simply constructed, easily applicable, temperature-sensitive unit of the class described adapted to have its element which is resiliently engaged with a utensil conveniently controlled as to optimum height and contact pressure with the utensil; and the provision of a unit of the class described which is conveniently self-locking in any preferred position. Other objects and features will be in part apparent and in part pointed out hereinafter.

The invention accordingly comprises the elements and combinations of elements, features of construction, and arrangements of parts which will be exemplified in the structures hereinafter described, and the scope of which will be indicated in the following claim.

In the accompanying drawings, in which one of various possible embodiments of the invention is illustrated,

Fig. 1 is an enlarged vertical section through my new temperature-sensitive heat control unit, being taken on line 1—1 of Fig. 2; and,

Fig. 2 is a cross section taken on line 2—2 of Fig. 1.

Corresponding reference characters indicate corresponding parts throughout the several views of the drawings.

Referring to the drawings, numeral 1 shows a flat supporting bracket conveniently located on a gas range beneath its top heaters or burner heads, one of which is illustrated in dotted lines at numeral 3. The upper end of this head 3 is generally located at some distance below the upper surfaces of the adjacent grates 5. The head 3 usually has a hollow portion 7 providing a space for locating the control unit of the invention. The unit is constituted by a tubular standard 9, turned in at the top to form an inward flange 11 within which is a circular opening 13. Located within the opening 13 is a movable capsule 15, the hermetically sealed bottom 17 of which is outwardly flanged beneath the inward flange 11, as shown at 19. The flange 19 is terminated by a cup portion 21 slidable in the region of the tubular standard 9 below flange 11.

Standard 9 is provided with lateral punched-out lower openings 23, permitting inlet of air, as indicated by the lower darts 25. In its upper region, the standard 9 is provided with punched-out openings 27, permitting escape of this air, as indicated by the darts 29. When the openings 27 are punched out, tongues 31 are left, which are later bent inward under the cup 21. They are bent in after the capsule 15 has been inserted into the opening 13 and a coil spring 33 has been inserted into the cup 21. Thus the bent-in tongues 31 provide a seat for the spring which biases the flange 19 toward the flange 11.

2

Hermetically sealed in a central opening in the capsule bottom 17 is a tube 35, which is downwardly coiled as shown at 37. The lower end 39 of the coil is hermetically sealed into a passage 41 of a hollow brass nipple 43. This passage 41, through a cross passage 45, communicates with a bendable tube 47 which terminates in the usual thermostatic control unit for controlling the gas valve which supplies the burner 3.

At 49 is shown a filling tube adapted to be pinched off and hermetically sealed as shown at 51. This is for filling with suitable liquid the system 15, 35, 37, 47, and the usual liquid-filled part of said thermostatic control device. Suitable thermostatic control devices are known for the purpose and require no further description. The proper liquid fill for the purpose is also known and requires no further description.

Preferably, the coil portion 37 of the tube 35 is composed of metal of a sufficiently springy nature that this coil portion tends also to bias the capsule 15 outward, as does the spring 33. In fact, if this coil portion of the tube is made sufficiently hard and springy, the spring 33 might be dispensed with.

The lower margin 53 of the standard 9 is provided with ears 55, extending through coextensive notches 57 formed in the margin of a thimble 59. After placement in the notches, the ears 55 are bent in under the thimble 59 to form a clutching or driving connection. Both the nipple 43 and the thimble 59 are threaded in such a way as to produce a threaded fit of such a nature that the thimble 59 may be turned on the nipple to vary the height of the thimble. The fit is tight enough so that once an adjustment in elevation has been made of the thimble 59 its position will be maintained, but loose enough for convenient turning. The nipple 43 carries a reduced stud portion 61 which passes through a hole 63 in the bracket 1, the attendant shoulder 65 resting on the bracket. A nut 67, threaded to the stud portion 61 under bracket 1, rigidly holds the assembly in position on the bracket 1. The hole 63 is preferably placed concentrically to the axis of opening 7, so that the standard 9 will be centered therein.

By means of the above construction, the standard 9 may be turned by grasping it at its upper end. This turning controls the elevation of the top 69 of the capsule 15. The capsule 15 normally turns with the standard 9 and in doing so winds or unwinds coil 37 to some extent. If the coil becomes wound a substantial amount, slippage will occur between flanges 11 and 19. An elevation is selected which, when the top 69 is engaged by the bottom 71 of the utensil 73, will establish a clearance between the flanges 11 and 19. This assures contact pressure between the capsule 15 and the utensil under bias of the spring 33 and/or the coil 37. The result is a reliable heat-transmitting contact between the top of the capsule 15 and the bottom of the utensil 73. Undue temperature rise in the utensil 73 raises the temperature and consequently the pressure of the liquid fill of the capsule and parts 35, 37 and 47. This pressure operates the connected thermostatic control, which affects the gas control valve for burner 3 to reduce gas flow. Conversely, if the utensil cools, so does the liquid fill, which lowers its pressure and causes the thermostatic control to open the gas valve supplying the burner 3.

Among the advantages of the invention are the simplicity with which the elevation of the capsule 15 may be controlled, simply by turning the standard 9. The bendable tongues 31 for the spring 33 provide a convenient means for effecting assembly of the capsule 15 and spring 33 before these tongues 31 are bent in. Thereafter they maintain the assembly of the spring and capsule. Also, the tongues 31 are conveniently formed when the holes 27 are punched.

It will be noted that when the capsule 15 is assembled into the upper end of the standard 9, the coil 37 will be located in the standard. At this time nipple 43 will have been hermetically sealed to its lower end 39. Consequently, the then separate thimble 59 may be threaded onto the exposed nipple 43. The notches 57 in the thimble may then be slipped along the unbent ears 55 until the thimble seats upon the end portions of the standard 9 between the unbent ears 55. Thereupon the ears 55 may be bent in, to effect a clutch, so as to complete the assembly, ready for application to the bracket 1. Finally, rotation of the standard 9 is effected until the capsule 15 is in proper elevated position to be contacted by the bottom 71 of utensil 73 resting upon the tops of the grates 5.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

A temperature-sensitive heat control unit for use in connection with a cooking range top heater above which are fixed vessel-supporting grates and below which is a support; comprising a threaded nipple affixed to said support, a hollow standard threaded at its lower end to said nipple and extending upward, adapted to be

changed in elevation by threading on said nipple, said standard being formed at its upper end with an inwardly directed portion providing a passage, a temperature-sensitive fluid-containing capsule having a vessel-engaging portion extending upward through said passage and having an outwardly extending means adapted for motion-limiting engagement with said inwardly directed portion, said standard also having inwardly directed means spaced downward from said inwardly directed portion adapted to form a seat, a compression spring supported at its lower end upon said seat and engageable at its upper end with said capsule and adapted to bias said vessel-engaging portion upward through said passage, and a fluid-containing coiled tube connected at one end portion to said capsule and extending therefrom within said standard, the other end portion of said coiled tube having a connection with a fluid supply passage extending through said nipple, whereby the elevation of said capsule may be adjusted by turning said standard without positively turning the capsule, spring, coil or the coil connection with said fluid supply passage.
